UNITED STATES PATENT OFFICE.

JOHN CLARENCE GARVEY, OF HARTWELL, OHIO.

HOSE-HOLDER.

SPECIFICATION forming part of Letters Patent No. 731,172, dated June 16, 1903.

Application filed July 11, 1902. Serial No. 115,166. (No model.)

To all whom it may concern:

Be it known that I, JOHN CLARENCE GARVEY, a citizen of the United States, residing at Hartwell, in the county of Hamilton and State of Ohio, have invented certain new and useful Improvements in Hose-Holders, of which the following is a specification.

The object of my invention is to provide an improved holder for hose by means of which the stream may be directed in any desired direction and the hose easily moved.

My invention consists in the combinations and arrangements of parts hereinafter described and claimed.

15 In the drawings, Figure 1 is a horizontal section of a hose-holder embodying my invention; Fig. 2, a vertical section of the same; Fig. 3, an end view of the hose clamp and handle; Fig. 4, a horizontal section of a modified form of application of my invention; Fig. 5, a vertical section of the same; Fig. 6, an enlarged section on line 6-6 of Fig. 5, and Fig. 7 a vertical section showing a different form of mounting for the hose clamp and handle.

Reference-letter A denotes a standard; B, a hose-reel; C, a hose-clamp, and D a section of hose.

The standard A is preferably in the form 30 of a tripod, having hinged legs secured in tripod form by hooks a'. A handle a² may be provided for convenience in carrying.

On top of standard A is pivoted a hose-reel B, having hinged reel-arms b and vertical reel-bars b'. The pivot for reel B consists of a 35 rod b², secured in standard A by means of set-screw a³. The rod b² passes up through the bottom plate b³ of reel B and is set into a socket in the top plate b⁴. A pin b⁶ locks 40 the bottom plate b³ to rod b².

On top of reel B is mounted a standard c, in which is pivoted the hose-clamp C. The 45 hose-clamp consists of a body portion c', having at its ends upturned flanges c², notched to receive the hose. To form the clamping member, side pieces c³ are hinged to the body portion, notched to coöperate with the notches in flanges c² to hold the hose, and provided with hooks c⁴, engaging eyes c⁵. A handle c⁶ 50 connects side pieces c³ and furnishes a means for adjusting the direction of the stream or

carrying the apparatus. A spring c⁷ renders the clamp capable of clamping different sizes of hose. The hinged tripod-legs a and the hinged reel-arms b render the holder readily 55 collapsible and easily carried.

It will be noted that the pivoted mounting of clamp C and reel B permits the adjustment of hose-nozzle d to direct the stream in any desired direction and at any angle of elevation, while the reel B furnishes a convenient means for carrying the hose.

In Figs. 4, 5, and 6 I have illustrated a modified form of my invention, in which tripod A' and reel B' are non-collapsible or rigid, and 65 in Fig. 7 I have illustrated another modification of my invention, in which the reel is dispensed with and the clamp-standard c is pivoted directly on standard A'.

While I have illustrated and described the 70 preferred form of application of my invention, this is obviously capable of many variations without departing from its spirit. I therefore do not wish to be limited to the exact construction shown and described; but 75

What I claim as new, and desire to secure by Letters Patent, is—

1. In a hose-holder, the combination of standard A; reel B; and clamp C pivoted to swing vertically and horizontally and provided with hinged handle c⁶ and spring c⁷, substantially as specified.

2. In a hose-holder, the combination of standard A having hinged legs a; reel B having hinged arms b; and clamp C pivoted to swing vertically and horizontally and provided with hinged handle c⁶ and spring c⁷, substantially as specified.

3. In a hose-holder, clamp C pivoted to swing vertically and horizontally and provided with hinged handle c⁶ and spring c⁷, substantially as specified.

4. In a hose-holder, clamp C pivoted to swing vertically and horizontally, and provided with hinged handle c⁶ adapted to serve 95 as a means for carrying the holder, and for operating clamp c, substantially as specified.

J. CLARENCE GARVEY.
